UNITED STATES PATENT OFFICE

RALPH C. VAUGHN, OF NEW YORK, N. Y.

DESIGN FOR A TOILET ACCESSORY CONTAINER

Application filed March 11, 1933. Serial No. 47,437. Term of patent 7 years.

To all whom it may concern:

Be it known that I, RALPH C. VAUGHN, a citizen of the United States of America, residing at New York city, county of New York, borough of Manhattan and State of New York, have invented a new, original, and ornamental Design for a Toilet Accessory Container, of which the following is a specification reference being had to the accompanying drawing, forming part thereof.

The figure is a perspective view of a toilet accessory container showing my new design.

I claim:

The ornamental design for a toilet accessory container as shown.

RALPH C. VAUGHN,
